SAFETY DEVICE

Andrew M. Williamson, Atlanta, Ga.

Application January 5, 1950, Serial No. 136,947

10 Claims. (Cl. 187—31)

1

This invention relates to an improved safety device particularly adaptable to hold the clutch or operating lever of a hoisting engine.

Customarily, in present day practice, the hoisting engine is usually located on the ground and is in a remote point from the tower or supporting structure of a cage or the like for lifting materials and workmen to various levels of a construction job. The operator of the engine stands in a position where it is impossible for him always to see the elevator, cage or platform, and particularly to see workmen on the cage or on the construction levels immediately adjacent the cage. The customary practice is for the operator to be governed by a bell or light signal which can be given by anyone on any of the floors of a building under construction. While workmen are actually engaged in loading or unloading a cage, or are otherwise located in a position of danger, should the cage be moved, he oftentimes misunderstands the signal given or becomes confused and lowers or raises the cage before the workmen have an opportunity to move to a position of safety. Consequently, many workmen have been injured and killed as a result of such mistakes and misunderstandings. Therefore, one object of this invention is to provide a safety device that will eliminate accidents resulting from errors of judgment or signal to the hoisting engine operator.

Furthermore, in current day practice wherein adequate and positive safety devices are not provided relative to the hoisting equipment, workmen are hampered by the psychological fear of being caught in a position where injury can occur, and consequently their operations around the cage are hampered by this psychological fear. Accordingly, another object of this invention is to provide a safety device for construction work that will eliminate this psychological hazard and will permit the workmen to function more efficiently on their job.

A further object of this invention is to provide an improved system whereby the clutch lever or similar control of a hoisting engine may be positively locked in an inoperative position by any one of several individuals located at several different points, such as levels of a building under construction, remotely located from said clutch lever or similar control.

These objects may be accomplished by a preferred form embodying my invention, by providing a plurality of controls, such as switches or the like, at different located levels of a building under construction, and connecting said controls to a mechanism, such as a solenoid or the like;

2

which mechanism in turn operates a holding means such as an arm that cooperates with the clutch lever of a hoisting engine in such a way as to lock said lever in an inoperative position. This enables a workman located at any one of the several levels of the building under construction to actuate the control or switch on the level at which he is working to lock or hold the clutch lever out of engagement.

Other objects and advantages of this invention will become apparent as the discussion proceeds and when considered in connection with the accompanying claims and drawings, in which:

Fig. 1 is an elevation, partly in section of a conventional elevator tower diagrammatically showing the switches and safety bars embodying my invention;

Fig. 2 is a side elevation and diagrammatic view of that part of the safety device embodying my invention, which holds the clutch lever in an inoperative position;

Fig. 3 is a top plan and diagrammatic view of that part of the safety device shown in Fig. 2; and

Fig. 4 is an enlarged section of the switch and safety bar embodying my invention, which are located on the several levels of the construction job or the hoisting tower.

Turning now to a detailed description of the drawings, the numeral 5 designates a skeleton tower of conventional design located in position against a building 6, under construction. Openings 7 are located at various levels of the tower 5 and at which an elevator cage or platform 8 is adapted to stop.

The elevator cage 8 is lowered and raised by means of a conventional cable 9 which is connected to an ordinary drum or the like, operated by a donkey or other hoisting engine, all of which is conventional and is not shown in detail in the drawings. A clutch operating lever 10, which may be operated by hand or by foot, is connected to the conventional clutch and hold mechanism located on the hoisting engine. Mounted upon the clutch operating lever 10 is a plate 11, as shown in Figs. 2 and 3.

A platform or other suitable support 12 is mounted adjacent the clutch lever 10, and pivotally supported thereon at 13 is a lever 14. Upon one end of the lever 14 is a laterally extending finger 15 which is adapted to swing into position behind the clutch lever 10, as shown in Figs. 2 and 3. The plate 11 carried upon the clutch lever 10 prevents the finger 15 from falling in front of

the clutch lever 10 when it is in the operating position shown in dotted lines in Fig. 2, and can fall on the side of the lever 10 opposite the finger 15 only when the clutch lever is in an inoperative position, shown in solid lines in Fig. 2.

The opposite end of the lever 14 from the finger 15 pivotally carries a core 16 which slidably operates into a high voltage solenoid 17. A spring 18 holds the safety arm 14 normally in the dotted line position shown in Fig. 3 away from the clutch arm 10. When the solenoid 17 is energized, the core 16 is drawn into said solenoid and causes the lever 14 to move into the solid line position best shown in Fig. 3.

The electrical system for operating the solenoid 17 consists of a plurality of switches 20 which may be of conventional design and which are shown in detail here only for the purpose of clearly illustrating my invention. The switches 20 are normally closed, and each is provided with a housing 21 having a contact 22 therein that is insulated from the housing 21 and is connected to one side of a low voltage line 23. Pivotally mounted within the housing 21 is an arm 24 grounded to the housing 21, and carrying a second electrical contact 25. The housing 21 is grounded to the opposite side of the low voltage line 23. A plunger 26 is slidably mounted within the housing 21, as shown in Fig. 4, and is pivotally connected at 27 to the arm 24. A spring or other actuating means 28 constantly urges the plunger 26 upward in respect to the housing 21 when viewed in the position shown in Fig. 4. Thereby the contacts 22 and 25 are constantly urged into a closed position.

Associated with each switch 20 is a safety bar 30 which, preferably, should be of considerable weight. While said bar 30 may vary widely in form and shape, it is preferred to mount one of these bars across each of the openings 7 about a hinge point 31 at one end, and to position the bar so as to rest upon the plunger 26 at its opposite end. The bar 30 may be mounted on pivot 31 and lowered and raised in front of the opening 7, or it may be entirely removable therefrom. It serves the dual purpose of an obstruction to the opening 7 when the cage is not at a level, in which position it holds the plunger 26 in a depressed position with the switch contacts 22 and 25 open.

It is to be here noted that the switches 20 are connected in parallel to the low voltage line 23. However, it is obvious to those skilled in the art, that by slightly modifying the circuit, to be described hereinafter, the switches 20 could be connected in series with the low voltage line 23, the contacts 22 and 25 being reversed so that they are normally closed and the solenoid 17 and plunger 16 also reversed. Thus modified, my invention would function equally as well as described herein.

Low voltage lines 23 are connected to a step-down transformer 32 and are in series with a low voltage solenoid 33. The step-down transformer 32, preferably, should supply 24 volts or less to the low voltage line 23, and the primary thereof is connected to the customary 110-volt source of electric current supply.

The solenoid 33 actuates a core 34 upon which a switch member 35 is carried, as shown in Fig. 2. The switch member 35 closes contacts 36, which are in series with an electrical connection 37 running to one side of the solenoid 17. The other side of the solenoid 17 is connected to a line 38. The lines 37 and 38 are directly con-

nected to the 110-volt source of electric current supply.

The operation of my safety device is explained as follows:

5 When any one of the bars 30 is lifted from the plunger 26, as shown in Fig. 1 at a level designated L, the switch contacts 22 and 25 will be closed. This will energize solenoid 33 and will cause the core 34 to be drawn thereinto, as shown in solid lines in Fig. 2. This will close the bar 35 on the contacts 36, and thus solenoid 17 will be energized, pulling core 16 thereinto, as shown in dotted lines in Fig. 3. When core 16 is pulled into the solenoid 17, the lever 14 is caused to swing about its pivot 13 and to take the position shown in the full lines in Fig. 3.

Provided the clutch lever 10 is in its inoperative position shown in solid lines in Fig. 2, the finger 15 will drop into place behind the clutch lever 10 and will remain there as long as solenoid 17 is energized. When finger 15 is behind clutch lever 10 it will be impossible for the operator to throw the clutch lever 10 into its operating position and thereby start the lowering or raising of the cage 8.

When the workman at a floor level is ready to have the cage 8 moved, he again replaces the safety bar 30 and thereby opens the switch 20, which cuts off the current to solenoid 33 and thereby, in turn, releases the lever 14, which again permits the engine operator to throw the clutch lever 10 into its operating position and cause the cage 8 to raise or lower, as desired.

It will be seen from the foregoing explanation that the safety device shown and described above enables a workman on any level where a switch 20 is located, to positively lock the clutch lever 10 from being thrown into its operating position once it is thrown into its inoperating position. Any workman located on any floor at which the cage 8 is not located may actuate the safety mechanism merely by raising the bar 30 and guarantee that the cage will not be lowered onto, raised to, or past, the level on which he is working at any time he feels he may be in a position of danger relative to said cage 8.

Modifications and changes in my invention may be resorted to without deviating from the spirit thereof, such as adapting the safety device to an electric switch operating an electric motor, or to a valve lever of a steam engine. A plurality of levers 14 may be provided simultaneously on jobs where there is more than one hoisting tower with more than one hoisting engine and lever 10. The voltages, types of solenoids, and switches, may also be varied without departing from the spirit of my invention.

I claim:

1. A safety device for a hoisting engine controlling the movement of an elevator associated with a building under construction comprising a clutch lever for controlling said hoisting engine, a support adapted to be located adjacent said clutch lever, an arm pivotally mounted on said support, a finger carried by said arm adapted to lock said clutch lever in an inoperative position, actuating means connected to said pivoted arm, and a plurality of controls connected to said actuating means, each of said controls adapted to be located at a level of said building under construction remote from said clutch lever whereby the clutch lever can be positively locked in an inoperative position from any level of the building under construction.

2. A safety device for a hoisting engine hav-

ing a clutch lever controlling the movement of an elevator associated with a building under construction comprising a support adapted to be located adjacent said clutch lever, a pivoted arm mounted on said support, a finger carried by said arm adapted to lock said clutch lever in an inoperative position, a plate mounted on said clutch lever positioned to prevent said finger from locking said clutch lever in an operative position, actuating means connected to said pivoted arm, and a plurality of controls connected to said actuating means, each of said controls adapted to be located at a level of said building under construction remote from said clutch lever whereby the clutch lever can be positively locked in an inoperative position from any level of the building under construction.

3. A safety device for a hoisting engine controlling the movement of an elevator comprising a clutch lever for controlling said engine, solenoid actuated means for positively locking said clutch lever in an inoperative position, switch means for operating said solenoid and adapted to be located at a level of a structure, and electrical means connecting said switch means to said solenoid.

4. A safety device for a hoisting engine controlling the movement of an elevator associated with a building under construction comprising a clutch lever for controlling said engine, a support adapted to be located adjacent said clutch lever, an arm pivotally mounted on said support, a finger carried by said arm in position to lock said clutch lever in an inoperative position, a solenoid having a movable core therein connected to said arm, a switch adapted to be located at a level of the building under construction, and an electrical circuit connecting said switch to said solenoid.

5. A safety device for a hoisting engine having a clutch lever controlling the movement of an elevator associated with a building under construction comprising a support adapted to be located adjacent said clutch lever, an arm pivotally mounted on said support, a finger carried by said arm in position to lock said clutch lever in an inoperative position, a plate mounted on said clutch lever positioned to prevent said finger from locking said clutch lever in an operative position, a solenoid having a movable core therein connected to said arm, a plurality of switches adapted to be located at various levels of the building under construction, and an electrical circuit connecting said switches to said solenoid.

6. A safety device for a hoisting engine having a clutch lever controlling the movement of an elevator associated with a building under construction comprising a support adapted to be located adjacent said clutch lever, an arm mounted on said support, a finger carried by said arm in position to lock said clutch lever in an inoperative position, a high-voltage solenoid having a movable core therein connected to said arm, a low-voltage solenoid having a movable core therein, a switch operatively connected with said last-mentioned core, said switch being connected to said high-voltage solenoid.

7. A safety device for a hoisting engine having an operating lever controlling the movement of an elevator for hoisting materials to a building under construction, said building having openings therein located at different levels and communicating with landing levels of said elevator, comprising electrically actuated means for

locking said lever in an inoperative position, switch means for operating said electrically actuated means and adapted to be located at the various openings, electrical means connecting said switch means to said electrically actuated means, and closure bars associated with said switch means adapted to actuate said switch means and to close said openings.

8. A safety device for a hoisting engine having an operating lever controlling the starting and stopping of an elevator at openings located at various levels of a building under construction and remote from said hoisting engine, comprising a pivoted lever adapted to be mounted in co-operating relation with said operating lever, a finger carried upon one end of said pivoted lever adapted to positively lock the operating lever in an inoperative position, a plate mounted on said operating lever positioned to abut against said depending finger to prevent locking of the operating lever in an operative position, a plurality of switches, each of said switches adapted to be located at the several respective levels of said building under construction, a solenoid connected with said switches, a switch actuated by said solenoid, a second solenoid connected with said switch, means actuated by said last-mentioned solenoid and connected to the pivoted lever, and closure bars associated with the switches adapted to be located at the several respective levels of said building, each bar being adapted to actuate one of said first-mentioned switches and to close one of said openings.

9. A safety device for a hoisting engine adapted to control the starting and stopping of an elevator, comprising a lever having a catch on one end portion thereof, means pivotally supporting the lever intermediate the ends thereof, a normally deenergized electro-magnetic device connected with the opposite end portion of the lever for moving the lever in one direction, a spring connected with the lever at the opposite side of the pivotal support normally tending to move the lever in the opposite direction.

10. A safety device for a hoisting engine adapted to control the starting and stopping of an elevator, comprising a lever having a catch on one end portion thereof, means pivotally supporting the lever intermediate the ends thereof, a normally deenergized electro-magnetic device connected with the opposite end portion of the lever for moving the lever in one direction, a spring connected with the lever at the opposite side of the pivotal support normally tending to move the lever in the opposite direction, an electric circuit connected with the electro-magnetic device for operating said device, a switch connected in said electric circuit for controlling the operation thereof, an electro-magnetic device for controlling said switch, and a second circuit connected with the second electro-magnetic device for operating the latter.
